INTERLOCKING SLIDE FASTENER

Harry Bertram Grant, Birmingham, England, assignor to Hookless Fastener Company, a corporation of Pennsylvania

Application September 19, 1933, Serial No. 690,095
In Great Britain December 8, 1932

6 Claims. (Cl. 24—205)

My invention relates to interlocking slide fasteners and particularly to flexible coverings for concealing the metal members of the fasteners.

At the present time interlocking slide fasteners having flexible coverings for concealing the metal members of the fastener are operated by means of sliders which ride over the covering strips. Such fasteners possess the disadvantage that the coverings which are located between the edge surfaces of the fastener members and the slider, quickly become worn in use. Furthermore when the slider is provided with a locking device which takes the form of a metal prong engaging between the fastener members, this prong usually pierces one or the other of the covering strips when in the locked position and thereby tends to damage same.

An alternative method of covering the fastener has been suggested whereby the covering strips conceal both the slider and the members, the slider body in this case operating underneath the coverings. Difficulty is experienced in this construction in making the coverings lie flat on top of the members, in keeping the two abutting edges of the strips in close contact when the fastener is closed, and in preventing the slider body from appearing bulky beneath the covering.

The principal object of my invention is to provide an improved covered slide fastener, the coverings of which conceal both the members and the slider body, which will be free from the disadvantages enumerated above and at the same time, be of neat appearance.

A further object of my invention is to construct the fasteners and coverings in such a manner as to enable them to be manufactured in a quick, easy and inexpensive manner.

According to my invention the covering strips are applied in such a manner that the natural side pull on the mounting tape, to which the fastener members are attached, forces the coverings to lie flat against the metal surfaces of the members thus enabling the abutting edges to be in close contact along the whole length of the fastener.

In the accompanying drawing I have shown for the purpose of illustration, the preferred embodiment of my invention. In this drawing:

Fig. 1 shows a plan view of a covered fastener;
Fig. 2 is a cross-section through the fastener showing the fastener members clamped into position on the mounting tape and the coverings partly assembled;

Fig. 3 is a cross-section through one half of

the fastener showing the next step in the method of assembly;

Fig. 4 is a cross-section through the fastener showing the finished coverings;

Fig. 5 is a cross-section through the fastener 5 and the operating slider; and

Fig. 6 is a cross-section through half of the covered fastener showing an alternative method of arranging the fastener mounting tape and covering strip.

Referring to Fig. 1, the fastener comprises flexible mounting tapes 1, having fastener members 2 attached to their adjacent edges. Each of these fastener members has a pair of legs 3 which are clamped to the tape, and an interlocking end 4 which is adapted to connect with members of the opposite series in the well-known manner.

The operating slider 5 having a pull tab 6, is adapted to cause engagement or disengagement 20 of the fastener members as the slider is moved from one end to the other of the fastener. The tape is folded back upon itself as shown in Fig. 2, the lower portion being designated 1 and the covering strip portion 7. The edge is beaded by 25 folding it over a cord 8.

Fig. 3 shows the next step in the manufacture where the covering portion 7 is reversely folded and stitched through the fold to hold the covering portion against the fastener elements. Preferably additional side cords 9 are affixed closely adjacent and alongside the rows of fastener members which give the necessary depth to the covering strip to enable it to be built up to a slightly higher level than the top of the fastener 35 members.

In order that this cord may be sewn conveniently to the upper and lower parts of the fabric covers 1, during this operation the tape 1 is folded back into the position shown. When 40 the tape 1 is folded into its normal position as shown in Fig. 4, any slight tension in this tape in the direction of the arrows "A" has the effect of causing the covering 7 to lie close to the surface of the fastener members and at the same 45 time cause the two edges of the tape to butt against each other along the whole length of the fastener.

The fabric cover strips 1 are preferably made of a material which will have a fair degree of 50 stiffness. For example, a tightly woven linen or artificial silk may be used. It is desirable to have the strips washed and dried before they are applied so that they will not become more flimsy after they have been applied to the fastener.

Fig. 5 shows a section through the fastener and the slider 5, illustrating the manner in which the latter rides underneath the covering. As it is desirable that the width of covering should be as narrow as possible we make the upper wing 10 of the slider 5 flat, instead of with the usual side flanges. In cases where the covering is required to be of different material from the mounting stringer we use two binding cords, 11, 11, 10 as shown in Fig. 6, which are sewn on to the edge 12 of the tape 13 and of the covering 14, which are brought together as shown. The covering is arranged in such a manner that no difficulty is encountered in arranging the locking 15 prong of the slider so that when it is in the locked position the covering strips are not affected thereby. The whole of the operating portions of the fastener, with the exception of the pull tab, are concealed by the covering strips and the 20 slider makes metal to metal contact with the fastener members without wearing the covering strips.

While I have shown and described in this application one embodiment that my invention may 25 assume in practice it will be understood that this embodiment is merely for the purposes of illustration and description and that various other forms may be devised within the scope of my invention as defined in the appended claims.

30 What I claim as my invention is:

1. In an interlocking slide fastener, a pair of mounting strips, cooperating series of fastener members mounted along the edges of said strips, flexible covering strips attached to the mounting 35 strips and folded back over the sides of said fastening members so that their edges are in abutting contact, and means at the fold to space the folded portion away from said mounting strips so that it will tend to lie flat against the sides of 40 said fastening members.

2. In an interlocking slide fastener, a pair of mounting strips, cooperating series of fastener members clamped to the edges of said strips, cover strips one edge of each of which is clamped by 45 said fastener members, said cover strips being folded upon themselves so that each of the other edges overlies the sides of the fastening members,

and a series of stitches passing through said fold whereby the folded portion tends to lie against the fastener members.

3. In an interlocking slide fastener, a pair of mounting strips, cooperating series of fastener members clamped to the edges of said strips, a pair of flexible cover strips each having one edge clamped by one series of said fastener members and extending along said mounting strips, and folded back upon itself to overlie the sides of said fastener members, and a cord placed in the fold to space the folded portion from the mounting strip, and a row of stitching passing through the folded portion and the cord.

4. In an interlocking fastener, a pair of mounting strips, cooperating series of fastener members mounted along the edges of said strips and adapted to interengage when the fastener is closed, said fastener members having surfaces which lie above the plane of the mounting strips, a spacer member extending alongside each series of fastener elements, and cover strips overlying said surfaces of the fastener members and each having a portion extending to one side of said fastener members over said spacer member, said covering strips being sufficiently stiff and said spacer member being sufficiently close to said fastener members that the covering strips will normally lie flat against the surfaces of the fastener members although having sufficient flexibility to permit movement of the slider between the fastener members and covering strips, said mounting strips extending laterally away from the fastener elements beyond the position of the spacer members.

5. In an interlocking fastener, the combination defined in claim 4 wherein said spacer member is spaced from said fastener members the minimum distance permitting free movement of the slider between said spacer member and fastener members.

6. The combination defined in claim 4, wherein said cover strips are made of tightly woven fabric material having sufficient stiffness to maintain the free edges thereof normally against the surfaces of the fastener members.

HARRY BERTRAM GRANT.
